UNITED STATES PATENT OFFICE.

PETER HARDMAN, OF WILLIMANTIC, CONNECTICUT.

PLAITING-MACHINE.

1,330,264.

Specification of Letters Patent. Patented Feb. 10, 1920.

Application filed October 7, 1918. Serial No. 257,088.

To all whom it may concern:

Be it known that I, PETER HARDMAN, a citizen of the United States of America, residing at Willimantic, Connecticut, have invented a new and useful Plaiting-Machine, of which the following is a specification.

My present invention is a machine for producing plaited products and particularly a product in the nature of a relatively flat cord.

The general objects of the invention are to provide a machine of this character which will be relatively simple in construction and positive and efficient in operation.

Special objects are to improve the carrier structure and the mechanism for imparting the necessary plaiting movement to the carriers; to provide simple and effective means for automatically controlling the feeding of

the separate strands from the moving carriers to the condenser, and to provide improved means for drawing off and reeling up the product.

Briefly stated, the invention resides in the combination of a plurality of carriers traveling on intersecting or connecting tracks, with means for propelling said carriers along said tracks, and means in the nature of traveling switches for shifting the carriers alternately from one track to the other.

The carriers are of special construction, as will appear as the specification proceeds, and the other features of the invention such as the take-up and the reeling mechanism all will be fully considered as the specification proceeds.

In the accompanying drawings, I have illustrated the invention as embodied in a practical commercial form, but it will be understood that the invention is not limited to this particular form, inasmuch as changes and modifications may be made without departure from the true spirit and scope of the invention.

In said drawings:

Figure 1 is a front view of the complete machine; with the plaited cord shown broken away at the take-up rollers.

Fig. 2 is a side view thereof partly broken away to show the gearing.

Fig. 3 is a plan view of the bed of the machine on a larger scale.

Fig. 4 is a front view of the gearing and transfer mechanism, the base of the machine appearing in section.

Fig. 5 is a horizontal sectional view taken

substantially on the plane of the line 5—5 of Fig. 4.

Fig. 6 is a vertical sectional view of the gearing and transfer mechanism taken substantially on the plane of the line 6—6 of Fig. 3.

Generally speaking, the machine consists of a bed or table 15 supported on a suitable base or frame 16 and provided with tracks or run-ways for the carriers 17 which carry the strands 18, said strands meeting at the condenser 19, from which the product is drawn off by the take-up rollers 20—21, the finished plaited cord 23 being then wound on a reel 24.

The carriers travel on intersecting or connecting paths having the general configuration of a figure 8. The outline of such paths is well illustrated in Fig. 3 wherein it will be seen that the bed plate is formed with two substantially circular openings 25 and 26 therethrough, the peripheries of such openings meeting or overlapping as indicated at the point 27 to provide the intersection or connection between the paths for the transfer of the carriers from one end to the other of the figure 8 path-way.

Operating in the circular openings 25 and 26 in the bed plate are the sprockets 28 and 29, said sprockets having the reduced rim or flange portions 30 and 31 respectively, overlapping at the point of intersection of the two paths, as indicated, and provided with registering equi-distantly spaced pockets or recesses 32 therein to receive correspondingly spaced studs on the carriers.

The carriers, as shown in the drawings, consist of spaced top and bottom plates or shoes 33 and 34 held in vertically spaced relation by the connecting studs 35 which have portions 36 dependent beneath the bottom shoe 34 for engagement with the switching mechanism to be described. The upper shoes 33 bear on top of the sprockets and the upper surface of the bed plate, and the lower shoes 34 are disposed beneath the sprockets and the under surface of the bed plate, while the studs or pins 35 work in the pockets 32 in the rims of the sprockets.

In the construction illustrated, the sprockets 28 and 29 are carried by the tubular shafts 37 and 38 journaled on the supporting posts or studs 39 and 40 disposed concentrically within the circular track openings 25 and 26 and mounted on the transverse bracket or base plate 140. These tubu-

lar sprocket shafts as clearly shown in Fig. 6, are geared to rotate in unison by intermeshing gears 41 and 42 fast on said shafts. In the case shown, power is applied to the 5 sprockets by means of a shaft 43 provided with fast and loose pulleys 44-45 thereon and carrying on its inner end a miter gear 46 in mesh with a miter gear 47 on the lower end of the sprocket shaft 38.

10 The carriers are transferred alternately from one path to the other by traveling switches or transfer devices shown in the form of segmental guides 48-49-50 and 51. These transfer segments are shown as 15 disposed concentric to the two sprocket centers (see Fig. 5) and are shown as carried by the disk-like supports 52-53 which are connected together so as to rotate in unison by means of the gears 54-55 to which said 20 segment disks are fastened. The gearing and arrangement of these transfer segments furthermore is such that in the rotation of said parts the segments will pass the point of intersection of the two carrier paths alternately from opposite sides. This alternative 25 arrangement of the transfer segments is clearly illustrated in Fig. 5.

The purpose of the transfer segments at each side of the point of intersection of the 30 carrier paths is to take hold of the carriers as they approach the point of intersection or connection and transfer them alternately to the opposite sides. Engagement with the carriers is effected by means of the dependent 35 studs or projections 36 which extend down far enough below the lower shoes of the carriers to be engaged by the transfer segments.

In order that the transfer devices may 40 overtake the carriers and draw them over to the opposite paths from which they are traveling, said segments are caused to rotate at a higher rate of speed than the sprockets and hence the carriers which are propelled 45 by said sprockets. This increase in speed is attained in the machine illustrated by a change speed gear consisting of a relatively large gear 56 fast on the sprocket shaft 38 and meshing with a smaller gear 57 loose 50 on the other sprocket shaft 37 but connected with the gear 54 of the transfer member 52.

It follows from this construction that the 55 two sprockets being directly geared together will rotate at equal speed and likewise the two transfer devices 52, 53 being geared together will rotate at equal speed, but said transfer devices by reason of the speed-up gearing described will rotate at greater 60 linear speed than the sprockets.

In the particular machine herein shown, there are five carriers, each sprocket is equipped with five pairs of equi-distantly spaced propelling pockets and there are four 65 transfer segments, two associated with each

sprocket. The gearing is proportioned so that the transfer devices will make five complete revolutions to every four complete revolutions of the sprockets. As a result of this, the transfer segments will continually 70 overtake and transfer the carriers alternately to the opposite paths, and the proper timing of the parts will be continuously maintained.

To make the transferring action clear, I 75 have indicated the carriers 17 in Fig. 5 in dotted lines. In this view, the parts rotating in the direction of the arrows, the segment 49 is shown as having overtaken and transferred a carrier from the right hand 80 path-way over to the left hand path-way, and the segment 50 is shown as about to overtake and pass behind the leading pin 36 on the carrier approaching the point of intersection from the left hand side. As the 85 segment 50 overtakes and passes behind the leading pin 36 on the carrier, a recess or cut-out 58 intermediate the ends of the segment receives the second pin of the carrier, and in the further acceleration of said 90 segment passes behind the second pin, the segment thereby gaining hold on both the carrier pins and drawing said carrier over so as to carry both pins into engagement with the driving pockets in the rim of the right hand 95 sprocket. In corresponding fashion the left hand transfer segment 48 will overtake and transfer the carrier shown in the right hand corner of the figure, as such carrier approaches the point of intersection of the two 100 paths, transferring the same over to the left hand sprocket. The transfer devices thus alternately approaching the point of intersection from opposite sides serve to transfer the carriers alternately to the opposite 105 sprockets.

In view of the fact that the propelling 110 pockets in the overlapping rim portions of the sprockets register at the point of connection of the two paths, the segments need not actually shift the carriers laterally to any appreciable extent, as they simply need to pass behind the pins of the carriers to confine them to the pockets in the proper sprockets until after the point of intersection has been passed, whereupon the carriers will be retained in engagement with such propelling pockets by being guided in the tracks provided in the bed plate. The segments therefore, are active only at the point 115 of intersection of the two paths and are then merely called upon to guide the carriers sufficiently to insure their engagement and retention by the proper sprockets.

To prevent premature shifting of the carriers from one sprocket to the other, I have shown a control device in the form of a yielding switch 59 pivoted in the bed plate at 60 and normally retained in an intermediate position by the springs 61. This hold- 120

ing device fits into the cut-away portion 62 provided in the overlapping rims of the two sprockets, and by engagement with the dependent studs of the carriers serves to hold 5 said carriers engaged each with their propelling sprockets until the point is reached where the segments gain control of the carriers to shift them from one sprocket to the other.

10 The tracks in the bed plate for guiding the carriers may be cut down into the bed plate as indicated at 63 in Fig. 6, for the purpose of better guiding the carriers, the adjoining portions of the sprockets being 15 correspondingly cut down as indicated at 64 to form a complete guiding channel receiving the upper shoe portions of the carriers.

10 The condenser 19 where the strands are 20 collected is located directly above the point of intersection or connection of the two tracks or substantially above the center of the figure 8 design, by reason of which the carriers as they pass in alternation in re- 25 verse directions, lay the strands one over the other into a substantially flat plaited cord. The pitch or angle of the overlay may be varied by adjusting the condenser toward or away from the carriers, for which 30 purpose the condenser is shown carried by an arm 65 having a vertical sliding adjustment over a rib or track 66 on the post or supporting column 67, said condenser arm being secured in its adjusted position by 35 means of a set screw 68.

On the forward or leading end of the carrier is mounted an upstanding post 81 for carrying the strand tensioning and slack take-up devices.

40 The plaited product after leaving the condenser passes between the drawing off rollers 20-21 which are shown as being positively driven for the purpose of taking the cord from the condenser at a predetermined 45 speed. One of the rollers, the upper one 21, is shown journaled in the end of a link 97 pivotally supported at 98. This permits the separation of the rolls by simply lifting the upper roll. The upper roll may be re- 50 tained in its lifted position by means of the pivoted link 99 which is slotted to slidingly engage over the pin 100, the slot in said link being formed with a shoulder 101 at the lower end thereof so that upon lifting 55 the roller this link may be shifted slightly to engage the shoulder over the pin 100 whereupon the link will support the upper roll in its lifted position. The upper roll is shown provided with a gear 102 arranged 60 to mesh with the gear 103 of the lower roll, this latter gear being engaged in turn by the gear 104 to which is connected a sprocket 105. A sprocket chain 106 engages with said sprocket and passes over another 65 sprocket 107 on the base of the machine.

This latter sprocket is connected with a gear 108 which is in mesh with a gear 109, and gear 109 is connected with a worm gear 110 which meshes with a corresponding worm gear 111 driven by gear 41 on the sprocket 70 shaft 37. This provides a simple positive drive from one side of the sprocket shaft.

The reeling mechanism is driven from the opposite side of the sprocket shaft, the means for this purpose consisting of a worm 75 gear 112 in mesh with the opposite side of the worm gear 111, and driving a gear 113 connected by gears 114 and 115 with the reel shaft or spindle 116.

The reel 24 for the finished product is 80 coupled to the supporting spindle therefor in such a way as to compensate for the variations in diameter as the cord is wound thereon.

Another feature of the invention is a 85 special form of traverse consisting of a lever 127 pivoted on the base of the machine at 128 and provided with a cord guide 129 at its upper end overstanding the reel. This traverse carries a forwardly projecting pin 90 or roller 130 engaging in a groove 131 in the cam 132, said cam being mounted on the shaft 133 which is driven from the reel shaft by an upright connecting shaft 134 and worm gearing 135-136. This construction 95 provides the necessary gearing ratio and provides a quiet smooth drive for the traverse. The traverse lever 127 is guided and held forward in proper engagement with the cam by means of the forwardly projecting 100 track 137 over which said lever has a sliding bearing.

I claim:

1. In a plaiting machine, sprockets arranged with their rims adjoining and provided with propelling pockets therein, carriers having each a pair of dependent studs for engagement in a pair of said pockets and segmental transfer switches traveling concentric to said sprockets and arranged to engage the pairs of dependent studs, each of said segmental switches having a gap intermediate the ends thereof to admit one of the dependent studs.

2. In a plaiting machine, the combination 115 of a member having intersecting paths, carriers traveling in said intersecting paths, means for propelling the carriers along each path and switches rotating completely around axes and operating to opposite sides 120 of and traversing the intersection of said paths to transfer the carriers from one path to the other.

3. In a plaiting machine, the combination 125 of a member having intersecting paths, carriers traveling in said intersecting paths, means for propelling the carriers along each path, and switches rotating completely around axes and at opposite sides of and traversing the intersection of said paths,

- said switches operating in alternation to transfer the carriers from one path to the other.
4. In a plaiting machine, the combination of a member having intersecting paths, carriers traveling in said intersecting paths, means for propelling the carriers along said paths, switches traveling completely around axes and engaging the carriers at the intersection of the paths for transferring the carriers from one path to the other, and means for advancing said switches at a faster speed than the carriers to cause said switches to overtake the carriers.
5. In a plaiting machine, the combination of a member having intersecting paths, carriers traveling in said intersecting paths, means for propelling the carriers along said paths, and switches rotating completely around axes and operating on substantially corresponding intersecting paths for transferring the carriers from one path to the other.
6. In a plaiting machine, the combination of a member having intersecting paths, carriers traveling in said intersecting paths, means for propelling the carriers along said paths, and switches rotating completely around axes and alternately crossing the point of intersection of said paths from opposite sides for transferring alternate carriers to opposite paths.
7. In a plaiting machine, the combination of a member having intersecting paths, carriers traveling in said intersecting paths, means for propelling the carriers along said paths, and switches approaching the point of intersection of said paths alternately from opposite sides and traveling at faster speed than the carriers to overtake and transfer alternate carriers to opposite paths.
8. In a plaiting machine, the combination of a member having intersecting paths, carriers traveling in said intersecting paths, means for propelling the carriers along said paths, and transfer devices at opposite sides of and substantially traversing the point of intersection of said paths, the transfer device at each side of said point of intersection arranged to engage the carriers at the opposite side of said point.
9. In a plaiting machine, the combination of a member having intersecting paths, carriers traveling in said intersecting paths, means for propelling the carriers along said paths, and switches traveling in paths substantially corresponding to each carrier path, the switches of opposite paths operating in alternation and at a higher rate of movement than the carriers so as to overtake the same and the switch operating in one carrier path being arranged to engage a carrier in the other path at the point of intersection of the paths to transfer said carrier from said other path to the first path.
10. In a plaiting machine, the combination of a member having intersecting paths, carriers traveling in said intersecting paths, means for propelling the carriers along said paths, and switches arranged to overtake the carriers at the point of intersection of the paths and to transfer said carriers first to one path and then to the other.
11. In a plaiting machine, a member having intersecting paths, carriers, means for propelling said carriers on said intersecting paths and means rotating completely around axes for transferring successive carriers on the respective paths at the point of intersection of the paths alternately from one path to the other path.
12. In a plaiting machine, the combination of a member having intersecting paths, carriers traveling in said intersecting paths, means for propelling the carriers along said paths, switches for shifting successive carriers alternately from one path to the other, and means for yieldingly retaining the carriers engaged with the propelling means therefor for a period prior to and up to the moment of transfer from one path to the other.
13. In a plaiting machine, the combination of a member having intersecting paths, carriers traveling in said intersecting paths, means for propelling the carriers along said paths, switches for shifting successive carriers alternately from one path to the other and a yieldable switch near the point of intersection of the carrier paths for yieldingly holding the carriers in the act of transfer engaged with the propelling means therefor.
14. In a plaiting machine, carriers, sprockets for propelling said carriers on intersecting paths and transfer devices operating in paths substantially coincident with the sprockets but at a faster rate of movement than said sprockets to overtake and transfer the carriers from one sprocket to the other.
15. In combination, carriers, sprockets for propelling said carriers about paths of movement which intersect and arcuate switches traveling concentric to the sprockets at the point of intersection of the paths of movement and arranged to shift the carriers from one sprocket to the other.
16. In a plaiting machine, means providing intersecting tracks, carriers, sprockets for propelling the carriers along said intersecting tracks and switches substantially concentric to said sprockets and arranged to transfer the carriers at the point of intersection of the tracks from one sprocket to the other.
17. In a plaiting machine, means providing intersecting tracks, carriers engaged with said tracks, sprockets for propelling said carriers along said tracks, switches con-

- centric to said sprockets and means for transferring the carriers of the respective sprockets in alternation, passing the point of intersection of the tracks and at a different rate of movement from the sprockets to cause said switches to pick up the carriers at said point of intersection and transfer the carriers from one sprocket to the other.
18. In a plaiting machine, carriers, members for carrying and moving said carriers, said members being so related that the paths of movement of said carriers will intersect, and a switch rotating completely around an axis for shifting the carriers from one of said members to the other.
19. In a plaiting machine, means providing intersecting tracks, carriers traveling on said tracks, sprockets for propelling said carriers along said tracks, switches concentrically related to said sprockets with the switch on one sprocket arranged in alternating relation to a switch of the other sprocket and a system of gearing for rotating the sprockets in unison and the switches in unison but at a faster rate of speed than the sprockets.
20. In a plaiting machine, parallel sprocket shafts, sprockets carried thereby and having overlapping rims, carriers transported by said overlapping rims of the sprockets and switches substantially co-axial with said sprockets for transferring successive carriers carried by said sprockets from one sprocket to the other.
21. In a plaiting machine, parallel sprocket shafts, sprockets carried thereby and having overlapping rims, carriers transported by said overlapping rims of the sprockets, switches concentric to the sprocket shafts and traveling in alternation on overlapping paths, and gearing for driving said switches at a faster rate of movement than the sprockets.
22. In a plaiting machine, parallel sprocket shafts, sprockets carried thereby and having overlapping rims, carriers transported by said overlapping rims of the sprockets, switches concentric to the sprocket shafts and traveling in alternation on overlapping paths, and gearing mounted on the sprocket shafts for driving the switches at faster linear speed than the sprockets.
23. In a plaiting machine, a bed plate having intersecting curvilinear tracks, supporting studs concentric to said tracks, tubular shafts on said studs, sprockets carried by said shafts and operating in said tracks, carriers propelled by said sprockets, switches journaled on said tubular shafts and arranged for engagement with the carriers to transfer the same from one sprocket to the other, intermeshing gears fast on the sprocket shafts for driving the same in unison, intermeshing gears loose on said sprockets but fast to the switches and change-speed gearing between one of said loose switch gears and one of the sprocket shafts.
24. In a plaiting machine, sprockets provided with overlapping rims having registering pockets, carriers having studs received in said pockets and transferring switches traveling in intersecting paths concentric to the sprockets and arranged to engage the studs of the carriers.
25. In a plaiting machine, sprockets arranged with their rims adjoining and provided with propelling pockets therein, carriers having each a pair of dependent studs for engagement in a pair of said pockets and segmental transfer switches traveling concentric to the sprockets and having each a slot intermediate the ends of the same to admit a second carrier stud after the first carrier stud has been engaged by the leading end of the segmental switch.
26. In a plaiting machine, sprockets arranged with their rims adjoining and provided with propelling pockets therein, carriers having each a pair of dependent studs for engagement in a pair of said pockets, segmental transfer switches traveling concentric to the sprockets and having each a slot intermediate the ends of the same to admit the second carrier stud after the first carrier stud has been engaged by the leading end of the segmental switch and means for rotating said switches at faster speed than the sprockets and with the switches associated with the respective sprockets in alternating relation.
27. In a plaiting machine, a bed plate having intersecting carrier tracks, sprockets operating within the respective tracks and provided with overlapping rims having registering pockets therein, carriers guided by said tracks and having each a pair of dependent studs engaging said pockets, segmental switches traveling in intersecting paths concentric to the sprockets and passing the point of intersection of the tracks in alternating order, said segmental switches each having a slot therein to receive the second stud of a carrier after the first stud has been engaged by the leading end of the switch, and means for rotating said switches at faster linear speed than the sprockets.
28. In a plaiting machine, a bed plate having intersecting carrier tracks, sprockets operating within the respective tracks and provided with overlapping rims having registering pockets therein, carriers guided by said tracks and having each a pair of dependent studs engaging said pockets, segmental switches traveling in intersecting paths concentric to the sprockets and passing the point of intersection of the tracks in alternating order, said segmental switches each having a slot therein to receive the sec-

ond stud of a carrier after the first stud has been engaged by the leading end of the switch, means for rotating said switches at faster linear speed than the sprockets and a spring pressed holder disposed substantially at the intersection of the tracks for engaging the dependent studs of the carriers to hold each carrier engaged with its driving sprocket until the operative switch has 10 transferred the same to the adjoining sprocket.

29. In a plaiting machine, the combination with means providing intersecting paths, of a given number of carriers traveling in said intersecting paths, of a different number of switches traveling in substantially intersecting paths of movement concentric to the carrier paths for transferring the carriers from one path to the other.

20 30. In a plaiting machine, the combination with a given number of carriers, means for propelling said carriers on intersecting paths of movement including sprockets, rotating switches for transferring the carriers 25 from one sprocket to the other, the number of switches differing from the number of carriers, and means for rotating said switches a number of times equal to or a multiple of the number of carriers while 30 said sprockets are being rotated a number of times equal to or a multiple of the number of switches.

31. In a plaiting machine, an odd number of carriers, sprockets for propelling 35 said carriers on intersecting paths of movement, an even number of rotating switches for transferring the carriers from one sprocket to the other and means for rotating said switches an odd number of times 40 while the sprockets are rotating an even number of times.

32. In a five-strand plaiting machine, the combination of five carriers, sprockets for propelling said carriers on intersecting paths 45 of movement, four rotary switches for transferring the carriers from one sprocket to the other and means for rotating the switches five complete revolutions to four complete revolutions of the sprockets.

50 33. In a plaiting machine, the combination with a definite number of carriers, of sprockets for propelling said carriers on intersecting paths of movement and each having a number of carrier pockets equal to 55 the total number of carriers, rotary switches of a lesser number than the total number of carriers and means for rotating the sprockets and switches, the switches a number of complete revolutions equal to the 60 total number of carriers while said sprockets are rotating a number of complete revolutions equal to the total number of switches.

34. In a plaiting machine, sprockets arranged with their rims adjoining and provided with propelling pockets therein, carriers

having each a pair of dependent studs for engagement in a pair of said pockets, segmental transfer switches traveling concentric to said sprockets and arranged to engage the pairs of dependent studs, each 70 of said segmental switches having a gap intermediate the ends thereof to admit one of the dependent studs and means for progressing the said segmental switches at a faster rate of movement than the sprockets 75 to thereby cause the switches to take hold of the dependent studs after said studs have passed through the gaps in said switches.

35. In a plaiting machine, a substantially figure 8 track, carriers guided by the track, 80 means for progressing the carriers around the track, a rotary switch for shifting the carriers at the point of intersection of the loops of the figure 8 track, and a condenser for the strands from said carriers disposed substantially in line with said point of intersection.

36. In a plaiting machine, a substantially figure 8 track, carriers guided by the track, 90 a condenser for the strands from said carriers, means for moving the carriers around the track, a rotary switch for shifting the carriers to the proper part of the track, and resilient means for engaging the carriers just prior to the shifting by the rotary 95 switch.

37. In the combination set forth in claim 36, said resilient means engaging the carriers coming from each loop of the track 100 alternately.

38. In a machine of the character disclosed, a table provided with intersecting circular openings, sprockets rotating in said openings and provided with propelling rims overlapping at the point of intersection of 105 the two openings and carriers comprising spaced upper and lower shoes with a plurality of studs holding each of said shoes in spaced relation, said upper shoes bearing on the rims of the sprockets and on the adjacent 110 edge portions of the table and said lower shoes being disposed at the lower face of the rim portions of the sprocket and traveling beneath the adjacent edge portion of the table.

115 39. In a machine of the character disclosed, a table provided with intersecting circular openings, sprockets rotating in said openings and provided with propelling rims overlapping at the point of intersection of 120 the two openings and carriers comprising spaced upper and lower shoes with studs holding said shoes in spaced relation, said upper shoes bearing on the rims of the sprockets and on the adjacent edge portions 125 of the table and said lower shoes being disposed at the lower face of the rim portions of the sprocket and traveling beneath the adjacent edge portion of the table, the edge portion of the table adjoining the openings 130

therein having a track-way and the adjacent rim portions of the sprockets having corresponding track-ways to receive the shoes of the carriers, said studs by their engagement 5 with the sprockets preventing rotation of the carriers in either direction.

40. In a machine of the character disclosed, a table having intersecting circular openings therein, sprockets rotating in said 10 openings and provided with pockets in the rim thereof registering at the point of intersection of the openings in the table, carriers each comprising upper and lower shoes held in spaced relation by a plurality of connecting studs received in the registering pockets in the sprockets, the upper shoes of said carriers traveling on the upper face of the adjoining edge portions of the table and sprockets and the lower shoes traveling at 15 20 the lower face of the adjoining edge portions of the table and sprockets.

41. In a machine of the character disclosed, a table having intersecting circular openings therein, sprockets rotating in said 25 openings and provided with pockets in the rim thereof registering at the point of intersection of the openings in the table, carriers comprising upper and lower shoes held in spaced relation by connecting studs received 30 in the registering pockets in the sprockets, the upper shoes of said carriers traveling on the upper face of the adjoining edge portions of the table and sprockets and the lower shoes traveling at the lower face of the 35 adjoining edge portions of the table and sprockets, segmental switches beneath the sprockets and projections dependent from said carriers and engaged by said segmental switches.

40 42. In a machine of the character disclosed, sprockets provided with overlapping rims having registering pockets therein, carriers supported on the overlapping rim por-

tions of said sprockets and provided with dependent studs engaging in the registering 45 pockets and segmental transfer switches below the sprockets traveling concentric to the sprockets and disposed to engage the dependent carrier studs.

43. In a plaiting machine, the combination of means providing intersecting paths, carriers traveling in said intersecting paths, means for propelling the carriers along said paths, switches for shifting successive carriers alternately from one path 50 to the other, and a switch device substantially at the point of intersection of the shuttle paths for holding the carriers for a period prior to and substantially up to the moment of transfer engaged with the propelling means therefor. 55 60

44. In combination, carriers, sprockets for propelling said carriers in intersecting paths, and arcuate switches traveling concentric to the sprockets at the point of intersection of the paths and arranged to shift the carriers alternately from one sprocket 65 to the other.

45. In a plaiting machine, sprockets arranged with their rims adjoining and provided with propelling pockets therein, shuttles having each a pair of dependent studs for engagement in a pair of said pockets and segmental transfer switches traveling concentric to the sprockets and arranged to engage the pairs of dependent shuttle studs. 70 75

46. In a machine of the character described, carriers, a plurality of means for moving said carriers in paths of movement which substantially intersect, and switches, 80 each rotating completely around an axis for shifting said carriers so that each carrier will be moved first by one of said means and then by the other.

PETER HARDMAN.
